US00D846915S

(12) **United States Design Patent** (10) **Patent No.:** **US D846,915 S**
(45) **Date of Patent:** **** Apr. 30, 2019**

(54) **AIR MATTRESS**

(71) Applicant: **Quzhou Hua'ao Outdoor Products Co., Ltd**, Zhejiang (CN)

(72) Inventor: **Xiuya Huang**, Chongqing (CN)

(73) Assignee: **QUZHOU HUA'AO OUTDOOR PRODUCTS CO., LTD**, Quzhou, Zhejiang (CN)

(**) Term: **15 Years**

(21) Appl. No.: **29/631,131**

(22) Filed: **Dec. 27, 2017**

(30) **Foreign Application Priority Data**

Jun. 28, 2017 (CN) 2017 3 0275482

(51) **LOC (11) Cl.** **06-09**

(52) **U.S. Cl.**

USPC **D6/604**
